WINDOW BLIND STRUCTURE

Charles A. Chenier, Ottawa, Ontario, Canada
Application May 8, 1953, Serial No. 353,734

4 Claims. (Cl. 160—118)

This invention relates to new and useful improvements in window blinds.

Briefly, the present invention is designed to provide a convenient and practical window blind structure which may easily and readily be moved to closed or open position over a window, cupboard, or other like closable openings.

It is therefore one of the objects of the present invention to provide a device of this character wherein a series of connected slats may be moved to collapsed or expanded position over a window or the like.

Another object of the present invention is to provide a device of this character wherein the connected slats are arranged in a vertical plane and are movable in a horizontal plane.

A further object of the present invention is to provide a device of this character wherein the slats forming the blind are foldably connected in overlapping relationship one with another.

Still a further object of the present invention is to provide a device of this character which may be easily and quickly mounted upon or removed from existing curtain rods.

Still another and further object of the present invention is to provide a device of this character wherein a valance forms part of the window blind when in folded or partly expanded or partly folded positions.

Yet a further object of the present invention is to provide a device of this character which may be moved to any desired expanded or folded position over a window and wherein the innermost slats of opposed sets of curtains or blinds may be releasably connected together when the blind is in a closed position.

Having regard to the foregoing and other objects and advantages which will become apparent as the description proceeds and the details become known, the invention consists essentially in the novel combination and arrangement of parts hereinafter described in detail and illustrated in the accompanying drawings in which:

Fig. 1 is a front elevational view of an embodiment of the present invention showing the blinds constructed in two separate sections with one section in open and the other in closed position respectively.

Fig. 2 is a front elevational view similar to that illustrated in Fig. 1 with the folded and expanded valance section connecting the opposed curtain forming sections.

Fig. 3 is an enlarged plan view of Fig. 1 with opposite sections of the slats shown in expanded and partly folded or collapsed positions.

Fig. 4 is an enlarged plan view of the center portions of Fig. 2 with valance.

Fig. 5 is an enlarged elevational view of a slat member shown in detached form.

Fig. 6 is an enlarged elevational view of a fragmentary portion of the slats shown in expanded and partly folded or collapsed positions.

Fig. 7 is an enlarged sectional plan view showing a pair of slats connected by a ring or link.

2

Fig. 8 is a section taken on the line 8—8 of Fig. 5.

Fig. 9 is a sectional plan view showing the means for releasably connecting the inner slats when the blind is in expanded to window covering position.

Fig. 10 is an enlarged elevational view of a slat member in detached form with modified form of link or ring connecting perforations.

Fig. 11 is an enlarged elevational view of a section of the modified form of slats foldably connected one to another, and

Fig. 12 shows a modified form of mounting of the blind members.

Referring now to the accompanying drawings wherein the present invention is disclosed and where like numerals of reference designate corresponding parts in the various illustrations, the numeral 15 designates the window blind as a whole which, in the present instance, and for purposes of illustration, is shown as being composed of a pair of window blinds 16 and 17 which may, if desired, include a valance 18. The window blinds or curtains, it will be observed, are foldably and expandably supported in a vertical plane by a horizontally disposed curtain suspension or supporting rod 19. The curtain rod 19 is detachably connected to any well known type of supporting bracket 20 which in turn is secured to window frame 21.

Each section of window blinds is composed of a series of slat members 23 which may be fabricated from metal, plastic or other suitable material preferably in arcuate form in cross section. As more particularly illustrated in Figs. 1, 2, 3, 4, 6 and 7, the slats are connected one to another by means of ring or link members 24. The link or ring connections between the slats, it is observed, are sufficiently loose to enable the slats to be folded one upon the other without stress, when in collapsed or expanded form.

As exemplified in the various illustrations, the upper end of each slat member is formed with a relatively large opening 25 which enables the slat members to be movably mounted on the curtain support rod 19 in window blind form. Arranged on opposed sides of each slat member below the head thereof are a series of spaced single and double orifices 26 and 27 respectively. The orifices 26, it will be noted, are arranged adjacent the slat edge 45 and provide a ring or link engaging section 28 while the double orifices 27 are disposed inwardly of the slat edge and provide an intermediate ring engaging section 29 inwardly of the edge.

By this novel arrangement of slat orifices and ring engageable sections, the slat members may be connected one to the other by the ring or loop members in alternately overlapped relationship and by such connections two important results are accomplished. First, the overlap with the novel disposition of the connecting means 55 prevents the edges of the slat members from becoming jammed or locked during folding or expanding movement and second, when the blinds are in expanded position, one slat overlaps the other and forms a positive and continuous closure cover for a window or other opening.

In the modified form shown in Figs. 10 and 11, an orifice 27a arranged inwardly of the slat edge with a notch 27b, may be substituted for the dual orifices 27.

When the window blinds are moved to window covering positions, the opposite sections may be releasably locked to one another. The means for releasably locking the sections may take any practical form and in the present instance I illustrate the marginal edges of the innermost slats being formed with oppositely inturned and out-turned portions of arcuate or semi-circular form as indicated at 30 and 31 for releasable engagement one with the other as shown in Fig. 9. In addition to the foregoing and to facilitate "drawing" opposed curtains or

blinds toward each other or releasing the locked sections, each slat is formed with an elongated protruding fold 32 spaced inwardly from the edges to provide hand grips 33 and 34. This type of lock and handle may extend longitudinally throughout the length of the innermost slats or a lesser distance and thus not only lends a more pleasing appearance to the window blinds, but affords a convenient means for releasably locking the sections one to another.

Where it is so desired, pairs or numbers of pairs or sets of window blinds may be provided with the valance 18. As illustrated in Figs. 2 and 4, the valance, as in common practice, extends above and below the curtain support 19 and is foldably and expandably connected to the inner ends of the opposed sections 16 and 17 of the window blinds in the same manner that the slats of the main blinds are overlappingly connected one to another.

As shown in Fig. 2, the two innermost slat members 36 and 37 are shorter in length than the slats of the main sections 16 and 17 and are spaced slightly from the lower ends of the valance. This arrangement permits the main blinds to be folded or expanded without interfering with the folding or expansion movement of the valance.

From what has thus far been described, it will be seen that when the main blinds are in folded position, the section 18 expands to form the valance between the main blind sections. Conversely, when the main blind sections are expanded, the valance forming slats are folded between such main sections. The valance forming slats are connected one to another by rings or the like 38 in the same manner as the main blind section, with the outer slats thereof being connected to the second innermost slats of the main sections by means of rings or the like 40.

Releasable connecting means and hand gripping means similar to those provided for the innermost slats 36 and 37, are also provided for the blinds which include a valance. Thus blind sections may be used with or without a valance as shown in Figs. 1 and 2.

In the modified form of suspension means shown in Fig. 12, the relatively large opening 25 is dispensed with and a small opening 42 substituted therefor. Mounted in this opening is a slat hook ring 43, the hook being detachably engageable with the ring 44 connecting rollers 45, the rollers being movable on well known track structure 46.

In operation, the slat forming blind members are first collapsed or folded to align the series of orifices or openings 25 when the detached curtain support rod 19 is simply slipped through the openings. When this operation is complete, the curtain rod with blind sections is connected to the supporting brackets on opposite sides of the window frame. Where track support means are employed, hooks 43 are connected to roller rings 44. The slats forming the blinds are now arranged in a vertical plane and are movable in a horizontal plane to or from a folded or expanded position to be free of or to extend over the window as a covering blind, as desired. Should it become desirable or necessary to clean or wash

the blind sections, the rod 19 is simply released from its bracket supports and the slat members slipped off the rod after which they may be washed or otherwise cleaned. Where the track type is concerned, hook members 43 are simply released from the roller rings.

Where the blinds are provided with a valance, the blinds are folded or expanded in exactly the same manner as the sections without a valance. The folding operation of the valance however differs from that of the blinds for the reason that when the blind sections are folded the valance sections are expanded and when the blind sections are expanded, the valance sections are folded.

Many changes may be made in the above and many apparently widely different embodiments constructed without departing from the spirit or the essential characteristics of the invention. It is intended therefore that the present disclosure be interpreted as illustrative and not in a limitative sense.

What I claim is:

1. In window blind structure extendable over windows or openings, a series of vertically supportable horizontally movable relatively long slat members arranged in window blind forming sections, a series of relatively short slat members connected intermediate the relatively long slat members to form a valance between the blind forming sections, means for connecting the window blind forming sections and the valance forming sections to one another in overlapped relationship comprising a series of spaced loop members connecting the edges of one slat member to intermediate body portions of the next succeeding slat member for foldably and expandably connecting the blind forming sections and the valance forming sections to one another.
2. A device as claimed in claim 1 wherein the blind sections are each provided with lock engaging means for releasably locking the blind sections together when in blind closing position.
3. A device as claimed in claim 1 wherein the blind sections are each provided with handle means for moving the said blind sections forward and backward to closed and open positions.
4. A device as claimed in claim 1 wherein one slat member is retained substantially in continuous contact with the next succeeding slat member and the said blind sections are provided with lock engaging means on the marginal edges thereof for releasably locking the said sections together in closed position and handle means for moving the said sections forward and backward to closed and open positions.
